LID FOR BASKETS

Stinson Huston and Robert E. Huston,
Trinity, Tex.

Application May 22, 1934, Serial No. 727,002

9 Claims. (Cl. 217—124)

Our invention relates generally to lids for fruit and vegetable shipping baskets, and an important object of our invention is to provide lids of the character indicated which are much less subject 5 to being broken than presently used lids, and thereby enable packers and shippers to avoid the major part of the waste and loss now being suffered in the use of present types of lids.

Other objects and advantages of our invention 10 will be apparent from a reading of the following description in connection with the drawings, wherein for purposes of illustration we have shown preferred embodiments of our invention.

In the drawings:

Figure 1 is a top plan view of one embodiment 15 of the invention.

Figure 2 is a longitudinal vertical sectional view 20 through Figure 1 taken approximately on the line 2—2 and looking in the direction of the arrows.

Figure 3 is a top plan view of another embodiment 25 of the invention and

Figure 4 is a longitudinal sectional view through 30 Figure 3 taken approximately on the line 4—4 and looking in the direction of the arrows.

Veneer baskets used for shipping fruits and 35 vegetables are ordinarily equipped with two wire handles which are placed on opposite sides of the top rim of the basket, the purpose of the handles being to afford means for holding the cover of the baskets in place during transportation of the baskets. The covers now used are provided with a long slat the opposite ends of which extend beyond the periphery of the lid and engage the wire handles so that the cover is held 40 in place.

When the baskets are packed for shipment the contents are crowned or piled up above the top of the basket so that it is necessary to have a cover which will bend or spring to a concave form to 45 accommodate this "bulge pack". The bulge is especially high when the baskets are packed with vegetables such as spinach, carrots, or green corn, in which instances it is not uncommon to have a bulge of four inches above the top rim of the basket when the cover is to be put in place. This, of course, necessitates considerable bending and flexing of the cover, and it frequently happens that the presently used covers will not stand the necessary amount of bending without breaking. 50 The break usually occurs in the long slat whose opposite ends engage the basket handles, so that there is nothing left to adequately hold the cover in place, and the cover must be removed and thrown away and replaced. The loss of covers through this type of breakage is excessively great 55

and is a very serious matter in point of expense and in point of inconvenience which is occasioned.

The long slat referred to which is subject to the described breaking which is the main cause 5 of the inefficiency of the present basket covers is usually made of a single piece of relatively heavy veneer and is stapled across the other parts of the cover and also on the top. We have discovered that by making the long piece in two 10 or more parts or plies, arranged one above the other either in direct engagement or in spaced relation, that this long slat will regularly undergo bending and strains of the character indicated without breaking or fracturing, to a degree 15 not possible with the ordinary solid slat. We have also discovered that certain dispositions of the plies with relation to the other parts of the cover greatly increase the flexibility and strength of the cover and aid in the manufacturing at low cost of a strong, durable, and efficient cover which is much superior to any covers now known to us. Practical tests of the invention in comparison with the conventional covers have shown that our cover is about ten times more 20 efficient and less liable to breakage than the conventional types. 25

Referring in detail to the drawings, the numeral 5 refers generally to one embodiment of the invention which comprises the ring or hoop 30 6 which is formed of a suitably circularly bent piece of wood having the opposite ends overlapped as indicated at 7. Across the top edge of the hoop 6 and extending slightly beyond or radially outwardly of the hoop 6 at their opposite ends are the cross slats 8, 9, 10 and 11 which are spaced as indicated and secured to the upper edge of the hoop 6 by means of staples which pass downwardly therethrough and enter the upper edge of the hoop 6. The foregoing structure is common to several types of conventional basket covers or lids. 35

The numeral 13 generally designates the composite slat of the invention which is composed of the upper ply 14 and the lower ply 15. Instead of resting across the top or bottom of the cross slats 8, 9, 10 and 11 as is the case with ordinary slat, the piles 14, 15 rest against and engage the top and bottom of the cross slats as shown in Figure 2. Stapling 16 passing through 40 the upper ply 14 and the lower ply 15 and through the intermediate ones of the cross slats holds the piles and the cross slats firmly and flexibly secured together. It will be noted that the 45 staplings 16 pass through approximately the cen- 50

ter of the cross slats and are equally spaced longitudinally of the long slats 13, thereby distributing the strain and providing for uniform flexibility. The staplings are clinched both at the top and at the bottom.

Where the radially outward ends of the main slat 13 traverse the hoop 16 they are stapled as indicated at 17, 18, 19 and 20, the stapling passing downwardly through both plies 14, 15 of the slat 13 and entering the upper edge of the hoop 16. It is to be noted that the staplings 19, 20 also perform the office of holding the overlapping ends of the hoop 6 connected. If additional staplings (not shown) are used to hold the ends of the hoop together, the staplings 19, 20 assist these.

The remaining embodiment of the invention shown in Figures 3 and 4 comprises the rim or hoop 20 having the overlapped ends generally designated 21 and having stapled to its upper edge the pairs of crossed and overlapping cross slats 22, 23 and 24, 25, and the overlying diagonally arranged top slat 26.

The slats 24, 25 are placed to overlie the slats 22, 23, and the diagonal slat 26 overlies the slats 24, 25. Staplings 27, 28 traverse and connect together the diagonal slat 26 and both slats 25 and 22, while the stapling 28 traverses and connects the diagonal slat 26 and the cross slats 24 and 23.

The numeral 29 designates the main slat in this embodiment which comprises the upper ply 30 and the lower ply 31. These plies are placed diagonally with respect to the cross slats and at right angles to the top slat 26, with the top ply 30 resting on the top slat 26 and the upper side of the cross slats 23 and 25 and 24 and 22, at opposite sides of the top slat 26. Stapling 32 traverses the upper and lower plies of the main slat 25 and the cross slats 24 and 22, while stapling 23 traverses and connects the upper and lower plies of the main slat 29 and the cross slats 25 and 23.

Like the first described embodiment the radially outward end portions of the plies 30, 31 rest against each other and are traversed by staplings 34, 35 which enter the upper edge of the ends of the hoop and connect the ends of the hoop together; and the staplings 36, 37 which traverse the opposite end of the main slat 29 secure it to the diametrically opposite upper edge portion of the hoop. By the described arrangement the strains are equally distributed in all directions and the flexibility of the cover is obtained in the desired degree, without in any way rendering the same weaker than conventional types but rather strengthening the same. It will be obvious that this greater flexibility and greater strength and more perfect distribution of strains will usually prevent the breaking of the main slats 13 and 29 respectively of the respective embodiments so that the covers will not have to be thrown away or replaced, and the fruit will be maintained properly packed during shipment and transportation.

Although we have shown and described herein preferred embodiments of our invention, it is to be definitely understood that we do not desire to limit the application of the invention thereto, and any change or changes may be made in materials, and in structure and arrangement of parts, within the spirit of the invention and the scope of the subjoined claims.

Having thus described our invention, what we claim as new is:

1. In a flexible cover for fruit and vegetable baskets of the character described, a rim, cross

slats fastened across and to the upper edge of the rim, and a main slat secured to and upon the said upper edge of the rim and having end portions extending radially outwardly of the rim at diametrically opposite sides thereof, and said main slat being composed of at least two plies, one of said plies overlying said cross pieces and the remaining one of said plies underlying said cross pieces, and means securing the respective cross slats and plies together.

2. In a basket of the type described including a rim, cross pieces lying upon and secured to the upper edges of said rim, a diagonal slat overlying said cross pieces and having its opposite ends secured to the upper edge of the rim, and a main slat having radially outward end portions fastened to the upper edge of said rim at diametrically opposite points, said main slat being composed of at least two plies, the upper one of said plies overlying said diagonal slat and said cross pieces, and another of said plies underlying said cross pieces, and means connecting said plies to respective ones of said cross pieces.

3. A flexible cover for a basket of the type described, said cover comprising a rim for seating in the basket top, at least two cross slats lying across said rim and secured to opposite sides thereof, a main slat lying across said slats, said main slat being composed of a lower ply lying across said rim and secured to the underside of said cross slats and to the rim, an upper ply lying across said rim and secured to the top side of said cross slats and to the rim, the opposite ends of said plies being secured together.

4. A flexible cover for a basket of the type described, said cover comprising a rim for seating in the basket top, at least two cross slats lying across said rim and secured to opposite sides thereof, a main slat lying across said cross slats, said main slat being composed of a lower ply lying across said rim and secured to the underside of said cross slats and to the rim, an upper ply lying across said rim and secured to the top side of said cross slats and to the rim, the opposite ends of said plies being secured together, said main slat being disposed substantially at right angles to said cross slats.

5. A flexible cover for a basket of the type described, said cover comprising a rim for seating in the basket top, at least two cross slats lying across said rim and secured to opposite sides thereof, a main slat lying across said cross slats, said main slat being composed of a lower ply lying across said rim and secured to the underside of said cross slats and to the rim, an upper ply lying across said rim and secured to the top side of said cross slats and to the rim, the opposite ends of said plies being secured together, said main slat being disposed substantially diagonally with respect to said cross slats.

6. A flexible cover for a basket of the type described, said cover comprising a rim for seating in the basket top, at least two cross slats lying across said rim and secured to opposite sides thereof, a main slat lying across said cross slats, said main slat being composed of a lower ply lying across said rim and secured to the underside of said cross slats and to the rim, an upper ply lying across said rim and secured to the top side of said plies being secured together, said main slat being disposed substantially diagonally with respect to said cross slats, some of said cross slats lying across other of said cross slats.

7. A flexible cover for a basket of the type described, said cover comprising a rim for seating

in the basket top, at least two cross slats lying across said rim and secured to opposite sides thereof, a main slat lying across said cross slats, said main slat being composed of a lower ply lying across said rim and secured to the underside of said cross slats and to the rim, an upper ply lying across said rim and secured to the top side of said cross slats and to the rim, the opposite ends of said plies being secured together, 5 said main slat being disposed substantially diagonally with respect to said cross slats, some of said cross slats lying across other of said cross slats, and a top slat overlying some of said cross slats and the lower ply of said main slat and underlying the upper ply of said main slat. 10

8. A fruit basket top of the character described comprising a generally circular rim, cross slats lying across and secured at their opposite ends to opposite sides of said rim, a main slat composed of a lower ply engaging the undersides of said cross slats and lying across said rim, an upper ply 15

20

upper ply engaging the top sides of said cross slats and lying across said rim, the opposite ends of said plies being secured together and to said rim, and separate means for each cross slat connecting said plies to each cross slat. 5

9. A fruit basket top of the character described comprising a generally circular rim, cross slats lying across and secured at their opposite ends to opposite sides of said rim, a main slat composed of a lower ply engaging the undersides of said cross slats and lying across said rim, an upper ply engaging the top sides of said cross slats and lying across said rim, the opposite ends of said plies being secured together and to said rim, and separate means for each cross slat connecting 10 15
